HEAT EXCHANGER

Louis C. Pellegrini, St. Louis, Mo., assignor to Marlo Coil Company, St. Louis, Mo., a corporation of Missouri

Filed Aug. 18, 1958, Ser. No. 755,607
10 Claims. (Cl. 257—50)

This invention relates to improvements in heat exchanger. More particularly, this invention relates to improvements in steam-heated, air-heating, heat exchangers.

It is therefore an object of the present invention to provide an improved steam-heated, air-heating, heat exchanger.

It is frequently desirable in the manufacture of steam-heated, air-heating heat exchangers to make those heat exchangers so they have the tubes thereof alined in rows, and so the rows of tubes are laterally spaced apart. It would be desirable to mount all of the tubes of the various rows of tubes in just one set of fins because such an arrangement would obviate any and all of the misalignment of fins that always occurs when individually-finned rows of tubes are set in face-to-face relation. By obviating that misalignment, it is possible to decrease the accumulations of lint and dirt in the heat exchanger and thereby decrease the pressure drop across that heat exchanger. While it long has been recognized that it would be desirable to mount all of the tubes of the various rows of tubes in just one set of fins, it has heretofore been regarded as impractical to mount more than two rows of tubes in just one set of fins of a steam-heated, air-heating heat exchanger, particularly where that heat exchanger operates intermittently.

It has heretofore been regarded as impractical to mount more than two rows of tubes in just one set of fins of a steam-heated, air-heating heat exchanger because of the warping of the heat exchanger as the hot steam rushes into the tubes and the cold air engages the fins and the exteriors of the tubes. Under some extreme circumstances, the temperature of the steam can be as high as three hundred and eighty seven degrees Fahrenheit and the temperature of the air can be as low as thirty degrees below zero. The contractions of certain parts of the heat exchanger caused by the impingement of the very cold air on those parts of that heat exchanger coact with the expansions of the tubes of that heat exchanger caused by the inrush of the very hot steam into those tubes to cause a working and warping of the heat exchanger that is destructive. The present invention obviates this destructive working and warping of the heat exchanger and thereby makes it possible to make steam-heated, air-heating, heat exchangers which have at least four rows of tubes mounted in just one set of fins. It is therefore an object of the present invention to provide a steam-heated, air-heating, heat exchanger which has at least four rows of tubes mounted in just one set of fins.

The present invention reduces the contractions and expansions of the heat exchanger by mounting imperforate tubes in the fins and by introducing the steam into perforated tubes telescoped into those imperforate tubes. The present invention further reduces the contractions and expansions of the heat exchanger by introducing part of the steam at one end of the heat exchanger and by introducing the rest of the steam at the other end of that heat exchanger. The telescoping of the perforated tubes within the imperforate tubes minimizes the temperature gradient along the face of the heat exchanger, and the introduction of the steam from both ends of the heat exchanger also minimizes that temperature gradient. The overall result is that working or warping of the heat exchanger is minimized. It is therefore an object of the present in-

2

vention to provide a steam-heated, air-heating, heat exchanger wherein the steam is introduced into perforated tubes telescoped within imperforate tubes and wherein the steam is introduced at both ends of said heat exchanger.

The introduction of the steam at both ends of the heat exchanger is additionally advantageous where the steam is throttled. Ordinarily the throttling of steam in a steam-heated, air-heating, heat exchanger leads to the existence of cold spots at the far end of the heat exchanger, and to the issuance of unheated air from that end of the heat exchanger. With the heat exchanger of the present invention, all parts of the heat exchanger will be hot even when the steam is throttled.

Other and further objects and advantages of the present invention should become apparent from an examination of the drawing and accompanying description.

In the drawing and accompanying description several preferred embodiments of the present invention have been shown and described but it is to be understood that the drawing and accompanying description are for the purpose of illustration only and do not limit the invention and that the invention will be defined by the appended claims.

In the drawing:

FIG. 1 is a partially-broken, plan view of one embodiment of steam-heated, air-heating, heat exchanger that is made in accordance with the principles and teachings of the present invention,

FIG. 2 is a partially-broken, plan view of another embodiment of steam-heated, air-heating, heat exchanger that is made in accordance with the principles and teachings of the present invention,

FIG. 3 is a partially-sectioned, plan view of part of another embodiment of steam-heated, air-heating, heat exchanger that is made in accordance with the principles and teachings of the present invention,

FIG. 4 is another partially-sectioned, plan view through the heat exchanger of FIG. 3, and it is taken through the tube immediately above the tube shown in FIG. 3,

FIG. 5 is a sectional plan view of another embodiment of steam-heated, air-heating, heat exchanger that is made in accordance with the principles and teachings of the present invention,

FIG. 6 is a plan view of another embodiment of steam-heated, air-heating, heat exchanger that is made in accordance with the principles and teachings of the present invention,

FIG. 7 is a front elevational view of the heat exchanger of FIG. 6,

FIG. 8 is a sectional plan view, on an enlarged scale, of a portion of the heat exchanger of FIGS. 6 and 7, and it is taken along the plane indicated by the line 8—8 in FIG. 7,

FIG. 9 is a partially-broken, elevational view of the left-hand end of the heat exchanger of FIGS. 6 and 7,

FIG. 10 is a partially-broken elevational view of the right-hand end of the heat exchanger of FIGS. 6 and 7, and

FIG. 11 is a diagrammatic, plan view of still another embodiment of steam-heated, air-heating, heat exchanger that is made in accordance with the principles and teachings of the present invention.

Referring to the drawing in detail, the numeral 20 generally denotes the frame of a steam-heated, air-heating, heat exchanger that is made in accordance with the principles and teachings of the present invention. While that frame could be made in many different ways, it is shown as being made of a series of channel-like structural members. The frame 20 extends laterally outwardly beyond the edges of, and thereby protects, heat-exchanging fins

22. Each of those fins has been punched to provide four

laterally-spaced, vertically-directed rows of openings; and those fins will preferably be made from a metal having a high thermal conductivity such as copper, aluminum or the like. Imperforate-wall tubes 24, 26, 28 and 30 of metal having a relatively high thermal conductivity are disposed within the uppermost openings in the fins 22; and a number of identically similar tubes are within those openings in fins 22 which are below, but in vertical alignment with, those uppermost openings. As a result, four laterally-spaced, vertically-directed rows of tubes are mounted in the fins 22. Those various tubes will be suitably fixed within those openings in one of the ways known to those skilled in the art.

A condensate header 32 is provided at the left-hand end of the heat exchanger of FIG. 1; and the tubes 24, 26, 28 and 30 and their counterparts incline downwardly from right to left in FIG. 1 so the lowermost ends thereof are adjacent the condensate header 32. The tubes 24, 26, 28 and 30 and their counterparts extend into appropriate openings in the wall of the condensate header 32 so the condensate which forms in those tubes can readily drain into that header. A condensate return line 34 is connected to the condensate header 32 adjacent the bottom thereof, and that return line inclines downwardly from its connection with header 32 to provide ready drainage of the condensate.

A tube 36 which has a ninety degree bend intermediate the ends thereof and which has a number of openings or perforations 38 in one arm thereof extends through the right-hand end of the tube 24. The left-hand end of the perforated arm of tube 36 is closed, and the right-hand end of the tube 24 fits tightly around the right-hand end of the perforated arm of tube 36 and is sealed to that arm of that tube. The openings or perforations 38 are distributed both axially and circumferentially along the length of the said arm of the tube 36. A tube 40 which has a ninety degree bend intermediate the ends thereof and which has one arm thereof provided with openings or perforations 38 extends through the right-hand end of tube 30. The left-hand end of the perforated arm of tube 40 is closed, and the right-hand end of the tube 30 closely fits around the tube 40 and is sealed to it. The other arms of the tubes 36 and 40 extend to and communicate with a steam header 42. That header supplies steam to the tubes 36 and 40, and that steam will issue from the openings or perforations 38 and enter the imperforate tubes 24 and 30. A series of tubes, identically similar to the tubes 36 and 40, are mounted below but in vertical registry with the tubes 36 and 40, any they extend through the right-hand ends of the tubes which are below but in vertical registry with the tubes 24 and 30.

A tube 44 which has a ninety degree bend intermediate the ends thereof passes through an opening in the left-hand side of the condensate header 32, and the junction between that opening and that tube is hermetically sealed. One arm of the tube 44 extends through the header 32 and extends into the tube 26. That arm has a number of perforations 38 disposed along its length but its right-hand end is closed. A tube 46 which has a ninety degree bend intermediate the ends thereof passes through another opening in the left-hand side of condensate header 32, and the junction between that opening and that tube is hermetically sealed. One arm of the tube 46 extends through the header 32 and extends into the tube 28. That arm has a number of openings 38 disposed along its length, but its right-hand end is closed. The other arms of the tubes 44 and 46 extend to and communicate with a steam header 48. A number of tubes, identically similar to the tubes 44 and 46, are disposed below but in vertical registry with the tubes 44 and 46; and those tubes extend between the header 48 and those tubes which are below but in vertical registry with the tubes 26 and 28. A main steam supply pipe 50 extends to the header 48 and supplies steam thereto; and a smaller steam supply

pipe 52 extends between that header and the header 42 to supply steam to that latter header.

In the operation of the heat exchanger shown in FIG. 1, steam is introduced into the header 48 by the supply pipe 50, and some of that steam is introduced into the header 42 by the supply pipe 52. Part of the steam introduced into the header 48 will pass through the tubes 44 and 46, and their counterparts, and pass through the openings 38 to enter the tubes 26 and 28 and their counterparts. The perforated tubes 44 and 46, and their counterparts, tend to distribute the steam along the lengths of the imperforate tubes 26 and 28 and their counterparts; and that steam will engage the inner walls of the tubes 26 and 28 and their counterparts and thereby transfer its heat to those walls. As the steam transfers its heat it will condense, and the resulting condensate will flow toward the lowermost ends of tubes 26 and 28 and enter condensate header 32. The steam introduced into the header 42 will pass into the tubes 36 and 40, and their counterparts, and will pass through the openings 38 into the tubes 24 and 30 and their counterparts. That steam will engage the inner walls of the tubes 24 and 30, and their counterparts, and will transfer its heat to those walls. As the steam transfers its heat to those walls it will condense, and the resulting condensate flow toward the lowermost ends of tubes 24 and 30 and enter condensate header 32. The condensate formed in tubes 24 and 30, and their counterparts, will flow in the same direction in which the steam within tubes 36 and 40, and their counterparts, flows; whereas the condensate formed in tubes 26 and 28, and their counterparts, must flow in the opposite direction to which the steam within tubes 44 and 46, and their counterparts, flows.

It will be noted that one half of the steam supplied to the heat exchanger is introduced at the left-hand end of that heat exchanger, and that the rest of that steam is introduced at the right-hand end of that heat exchanger. This means that the temperature gradient along the face of the heat exchanger will be very small, and that the temperatures of most parts of the heat exchanger will be held within a completely workable and practical range. Further, this will still be the case when the steam is throttled. In prior, steam-heated, air-heating, heat exchangers, the steam has been introduced at just one end of the heat exchanger; and throttling of the steam permitted the opposite end of the heat exchanger to become cool. Consequently, the air issuing from that end of the heat exchanger was not heated adequately, and could produce a cool draft rather than a warm flow of air. With the heat exchanger provided by the present invention, all of the air issuing from that heat exchanger will be warmed, even when the steam has been throttled.

It will be noted that there is no misalignment of the heat-exchanging fins for the adjacent rows of tubes because all of the rows of tubes are mounted in just one set of fins. Hence, there is not the usual interruption to the smooth flow of air through the heat exchanger, there is not the usual frictional losses, and there is not the usual pressure drop.

Referring to FIG. 2, the numeral 60 denotes the frame of a heat exchanger, and that frame protects and supports fins 62. Each of those fins has been punched to provide four rows of aligned openings, and those openings accommodate four laterally-spaced, vertically-aligned rows of imperforate tubes. The uppermost tubes of those rows of tubes are denoted by the numerals 64, 66, 68 and 70. The tubes 64 and 66, and their counterparts, incline downwardly from right to left in FIG. 2, and their lowermost ends are connected to and communicate with the condensate header 72. A condensate return 74 inclines downwardly and away from the lower part of the header 72. The tubes 68 and 70, and their counterparts, incline downwardly from right to left in FIG. 2 and their lowermost ends are connected to and communicate with the condensate header 76. A condensate

return 78 inclines downwardly and away from the lower end of the header 76. If desired, one large condensate header could be used instead of the two headers 72 and 76; and, if desired, some of the rows of tubes could be set to drain toward a condensate header at the right-hand end of the heat exchanger while the rest of the rows of tubes drained toward a condensate header at the left-hand end of the heat exchanger. Because of the possibility of using different numbers and arrangements of condensate headers, it will be understood that whenever the phrase condensate header is used herein or in the claims hereof it will be understood, unless expressly or impliedly indicated otherwise, to mean one or more condensate headers.

A tube 80 has a ninety degree bend intermediate the ends thereof, and one arm of that tube has perforations 38 therein. That arm of that tube extends through the right-hand end of the tube 64 and is sealed to that latter tube. Identically similar tubes are disposed below but in vertical registry with the tube 80, and the arms of those tubes extend into the tubes which are the counterparts of tube 64. The left-hand ends of tube 80 and its counterparts are closed. The numeral 82 denotes another tube with a ninety degree bend intermediate its ends, and one arm of that tube has perforations 38. That arm of that tube extends through the right-hand end of the tube 68 and is sealed to that latter tube. Other tubes, identically similar to the tube 82, are below but in vertical registry with that tube and extend into the tubes which are the counterparts of the tube 68. The other arms of the tubes 80 and 82 and their counterparts extend to and communicate with the steam header 84.

The numeral 86 denotes a generally J-shaped tube which has the long arm thereof provided with perforations 38. That arm, which has its right-hand end closed, extends through an opening in the left side of the header 72 and extends into the tube 66. A number of tubes identically similar to the tube 86 are disposed below but in vertical registry with that tube, and they extend through other openings in the left side of header 72 and lodge within the tubes which are the counterparts of tube 66. The numeral 88 denotes another J-shaped tube which has its long arm provided with openings 38. That arm has its right-hand end closed, and it telescopes through an opening in the left side of header 76 and lodges in the tube 70. The counterparts of tube 88 also extend through openings in the left side of header 76 and lodge in the counterparts of tube 70. The short arms of the tubes 86 and 88 are connected to and communicate with the steam header 90. That steam header is connected to the steam header 84 by a steam supply pipe 94, and it receives steam from steam supply pipe 92.

The construction and operation of the heat exchanger shown in FIG. 2 is similar to that of the heat exchanger shown in FIG. 1; the principal differences between the two heat exchangers being in the interleaving of the oppositely fired or fed tubes of the heat exchanger of FIG. 2, and the use of two, rather than just one, condensate header. In each heat exchanger, two rows of tubes are fired or fed from the right-hand end of the heat exchanger and two rows of tubes are fed from the left-hand end of the heat exchanger.

Referring to FIGS. 3 and 4, the numeral 100 denotes the heat-exchanging fins of a single row heat exchanger. Those fins support a number of tubes 102 and 104 and their counterparts; and those tubes incline downwardly from left to right in FIGS. 3 and 4. The tubes 102 and 104, and their counterparts, are interleaved vertically; and the tube 104 and its counterparts have closed left-hand ends 128 while the tube 102 and its counterparts have openings in the left-hand ends 106 thereof.

Tube 108 and its counterparts have ninety degree bends intermediate the ends thereof; and while the right-hand ends of the long arms of those tubes are closed, a number of perforations or openings 38 are distributed axially

and circumferentially along those arms. The short arms of the tube 108 and its counterparts extend to and communicate with the steam header 120; and the long arms of those tubes telescope through and are sealed to the openings in the left-hand ends of the tube 102 and its counterparts. The right-hand ends of the tube 102 and its counterparts extend to and communicate with the condensate header 122. That condensate header is provided with a condensate return 124 which inclines downwardly and away from the bottom of the header 122.

Tube 126 and its counterparts have ninety degree bends intermediate the ends thereof, and the long arms of those tubes extend through openings in the right side of the condensate header 122 and telescope into the tube 104 and its counterparts. The right-hand ends of tube 104 and its counterparts extend to and communicate with the condensate header 122. The other arms of the tube 126 and its counterparts extend to and communicate with the steam header 130. That steam header is connected with the steam header 120 by a steam pipe 134; and the steam header 130 is supplied with steam by a steam supply pipe 132.

In the operation of the heat exchanger shown in FIGS. 3 and 4, part of the steam from supply pipe 132 passes into the header 130 and then into the tube 126 and its counterparts. That part of the steam passes outwardly through the openings 38 and enters the imperforate tube 104 and its counterparts. The rest of the steam passes through supply pipe 134 to header 120 and then into the tube 108 and its counterparts. Thereafter, the said rest of the steam passes through the openings 38 and enters the imperforate tube 102 and its counterparts. The steam which enters the imperforate tubes 102 and 104 and their counterparts will engage the inner surfaces of those tubes and transfer their heat to those tubes. In doing so, that steam will condense; and the resulting condensate will flow toward the lowermost ends of tubes 102 and 104 and their counterparts and enter the condensate header 122. Thereafter, that condensate will drain through the condensate return 124. The operation of the heat exchanger of FIGS. 3 and 4 is similar to the operation of the heat exchangers of FIGS. 1 and 2; the principal differences being that the heat exchanger of FIGS. 3 and 4 is a single row heat exchanger and that the tubes 102 and 104 and their counterparts are vertically interleaved.

Referring to FIG. 5, the numeral 140 denotes a number of heat-exchanging fins which are punched to provide two laterally-spaced rows of aligned openings. Those openings accommodate imperforate tubes 142 and 144 and their counterparts; and those tubes incline downwardly from left to right in FIG. 5. The right-hand ends of those tubes extend to and communicate with a condensate header 150. A tube 154 and its counterparts have ninety degree bends intermediate the ends thereof, and the long arms of those tubes extend through and are sealed to the ends 146 of the tube 142 and its counterparts. The right-hand ends of the long arms of tube 154 and its counterparts are closed, but those arms have openings 38 along the lengths thereof. The other arms of tube 154 and its counterparts extend to and communicate with the steam header 156.

The tube 144 and its counterparts have closure 148 at the left-hand ends thereof. Tube 158 and its counterparts have ninety degree bends intermediate the ends thereof, and the long arms of those tubes extend through openings in the right side of the condensate header 159 and lodge within the tube 144 and its counterparts. The left-hand ends of tube 158 and its counterparts are closed, but the long arms of those tubes have openings 38 along the lengths thereof. The junctions between the long arms of tube 158 and its counterparts and the openings in the right side of header 159 are hermetically sealed. The short arms of tube 158 and its counterparts extend to and communicate with the steam header 160. A steam sup-

ply pipe 164 extends between the header 160 and the header 156, and a main steam supply pipe 162 is connected to the header 160.

The heat exchanger shown in FIG. 5 is similar to the heat exchanger shown in FIGS. 3 and 4; the principal difference being that the heat exchanger of FIG. 5 has two rows and has all of the tubes in one row fed at their left-hand ends and has all of the tubes in the other row fed at their right-hand ends. The steam that passes through tubes 154 and 158 and enters tubes 142 and 144 will condense; and the resulting condensate will flow downwardly to the condensate header 150 and drain out through the condensate return 152.

Referring to FIGS. 6-10, the numeral 170 denotes a frame for a heat exchanger, and the numeral 172 denotes a steam supply pipe. That pipe is connected to the steam header 174, and a steam supply pipe 176 extends from the header 174 to the steam header 178. As indicated particularly in FIG. 7, the steam pipes 172 and 176 are located approximately midway between the top and bottom of the heat exchanger. A condensate return 180 is provided, and that return communicates with the bottom of condensate header 182.

A number of heat-exchanging fins 171 are mounted in the frame 170; and those fins are punched to provide two laterally-spaced rows of openings. Imperforate tubes 184 and 188 and their counterparts are mounted in those openings to define two laterally-spaced rows of tubes. Those tubes incline downwardly from right to left in FIGS. 6 and 7, and the lowermost ends of those tubes are connected to and communicate with the condensate header 182. The right-hand ends of the tube 184 and its counterparts are closed, and the right-hand ends of the tube 188 and its counterparts are partially closed. Tube 190 and its counterparts have ninety degree bends intermediate the ends thereof, and the long arms of those tubes have their ends closed and have openings 38 along the lengths thereof. A tube 186 and its counterparts have bends of approximately two hundred and ninety degrees therein; and the long arms of those tubes have the ends thereof closed and they extend through openings in the left side of header 182 and lodge within tube 184 and its counterparts. The junctions between the tube 186 and its counterparts and the openings in the left side of header 182 are hermetically sealed. The other arms of tube 190 and its counterparts extend to and communicate with steam header 178, and the other arms of tube 186 and its counterparts extend to and communicate with steam header 174. The heat exchanger of FIGS. 6-10 is similar to the heat exchanger shown in FIG. 5, but the steam headers and the interconnecting steam supply pipe 176 have been protected by the frame 170.

Referring to FIG. 11, the numeral 200 denotes a steam supply pipe which is connected to a steam header 202. A steam supply pipe 204 extends from the header 202 to the header 208, and that pipe has a shut off valve 206 intermediate the ends thereof. The heat-exchanging fins 210 of the heat exchanger of FIG. 11 are punched to provide two laterally-spaced rows of openings, and tubes 212 and 216 and their counterparts are mounted in those openings. Tube 212 and its counterparts extend between the steam header 202 and the condensate header 214; and tube 216 and its counterparts extend from the steam header 208 to the condensate header 218. The two headers 214 and 218 are connected together by a condensate line 220, and a condensate return 222 extends downwardly and away from the lower end of the header 218.

In operation, the valve 206 can be opened to supply steam to the heat exchanger at both ends; and where that is done, part of the steam will pass from steam header 202 through tube 212 and its counterparts to the condensate header 214, and the rest of the steam will pass from steam header 208 through tube 216 and its counterparts to the condensate header 218. In the heat exchanger of FIG. 11, perforated inner tubes are not used.

When desired, the valve 206 can be set to reduce the amount of steam introduced into the right-hand end of the heat exchanger.

In each of the heat exchangers shown by the drawing, heat-transferring fins have been provided on the imperforate heat exchange tubes. However, the present invention is not restricted to use with heat exchangers utilizing finned tubes; that invention being usable with steam-heated, heat exchangers that utilize bare tubes.

Whereas the drawing and accompanying description have shown and described several preferred embodiments of the present invention, it should be apparent to those skilled in the art that various changes may be made in the form of the invention without affecting the scope thereof.

What I claim is:

1. A steam-heated, air-heating, heat exchanger that comprises a frame, a plurality of heat-exchanging fins disposed within said frame, each of said heat-exchanging fins having a plurality of openings therein, said openings being grouped and aligned to define at least four laterally-spaced rows of openings, a plurality of imperforate-wall tubes mounted in said openings in said heat-exchanging fins to form at least four laterally-spaced rows of imperforate-wall tubes, said imperforate-wall tubes being inclined to the horizontal and each of said imperforate-wall tubes having its lower end adjacent one end of said frame, a condensate header that is adjacent said one end of said frame and that is connected to and communicates with the lower ends of said imperforate-wall tubes, a steam header adjacent said one end of said frame, a second steam header adjacent the opposite end of said frame, a steam pipe communicating with and extending between said steam headers, a plurality of perforate-wall tubes that communicate with and extend from the first said steam header and that telescope into and through the lower ends of some of said imperforate-wall tubes, a second plurality of perforate-wall tubes that communicate with and extend from said second steam header and that telescope into and through the upper ends of the rest of said imperforate-wall tubes, each of said perforate-wall tubes having a bend therein intermediate its steam header and its imperforate-wall tube, a portion of said perforate-wall tubes being sealed to and extending through said condensate header to telescope into their imperforate-wall tubes, said steam headers and said perforate-wall tubes directing steam into the opposite ends of said heat exchanger, the perforations in each said perforate tube being spaced throughout its length within the imperforate tube to provide uniform heating of said heat exchanger even when said steam is throttled, said bends in said perforate-wall tubes accommodating expansion and contraction of said perforate-wall tubes and of said imperforate-wall tubes, the upper ends of said some imperforate-wall tubes being closed, the upper ends of said rest of said imperforate-wall tubes being sealed to said second plurality of perforate-wall tubes, said frame extending laterally outwardly beyond the sides and ends of said headers, the condensate in said some imperforate-wall tubes flowing in a direction opposite to the direction of flow of the steam in the first said plurality of perforate-wall tubes, the condensate in said rest of said imperforate-wall tubes flowing in the same direction as the flow of the steam in said second plurality of perforate-wall tubes.
2. A steam-heated, air-heating, heat exchanger that comprises a frame, a plurality of heat-exchanging fins disposed within said frame, each of said heat-exchanging fins having a plurality of openings therein, said openings being grouped and aligned to define laterally-spaced rows of openings, a plurality of imperforate-wall tubes mounted in said openings in said heat-exchanging fins to form laterally-spaced rows of imperforate-wall tubes, said imperforate-wall tubes being inclined to the horizontal and each of said imperforate-wall tubes having

its lower end adjacent one end of said frame, a condensate header that is adjacent said one end of said frame and that is connected to and communicates with the lower ends of said imperforate-wall tubes, a steam header adjacent said one end of said frame, a second steam header adjacent the opposite end of said frame, a steam pipe communicating with and extending between said steam headers, a plurality of perforate-wall tubes that communicate with and extend from the first said steam header and that telescope into and through the lower ends of some of said imperforate-wall tubes, a second plurality of perforate-wall tubes that communicate with and extend from said second steam header and that telescope into and through the upper ends of the rest of said imperforate-wall tubes, each of said perforate-wall tubes having a bend therein intermediate its steam header and its imperforate-wall tube, a portion of said perforate-wall tubes being sealed to and extending through said condensate header to telescope into their imperforate-wall tubes, said steam headers and said perforate-wall tubes directing steam into the opposite ends of said heat exchanger, the perforations in each said perforate tube being spaced throughout its length within the imperforate tube to provide uniform heating of said heat exchanger even when said steam is throttled, said bends in said perforate-wall tubes accommodating expansion and contraction of said perforate-wall tubes and of said imperforate-wall tubes being closed, the upper ends of said rest of said imperforate-wall tubes being sealed to said second plurality of perforate-wall tubes, the condensate in said some imperforate-wall tubes flowing in a direction opposite to the direction of flow of the steam in the first said plurality of perforate-wall tubes, the condensate in said rest of said imperforate-wall tubes flowing in the same direction as the flow of the steam in said second plurality of perforate-wall tubes.

3. A steam-heated, air-heating, heat exchanger that comprises a frame, a plurality of heat-exchanging fins disposed within said frame, each of said heat-exchanging fins having a plurality of openings therein, said openings being grouped and aligned to define at least four laterally-spaced rows of openings, a plurality of imperforate-wall tubes mounted in said openings in said heat-exchanging fins to form at least four laterally-spaced rows of imperforate-wall tubes, said imperforate-wall tubes being inclined to the horizontal to drain to the same end of the heat exchanger, a condensate header that is adjacent said frame and that is connected to and communicates with the lower ends of said imperforate-wall tubes, a steam header adjacent one end of said frame, a second steam header adjacent the opposite end of said frame, a steam pipe communicating with and extending between said steam headers, a plurality of perforate-wall tubes that communicate with and extend from the first said steam header, and that telescope into and through the ends of some of said imperforate-wall tubes, a second plurality of perforate-wall tubes that communicate with and extend from said second steam header and that telescope into and through the ends of the rest of said imperforate-wall tubes, each of said perforate-wall tubes having a bend therein intermediate its steam header and its imperforate-wall tube, a portion of said perforate-wall tubes being sealed to and extending through said condensate header to telescope into their imperforate-wall tubes, said steam headers and said perforate-wall tubes directing steam into the opposite ends of said heat exchanger, the perforations in each said perforate tube being spaced throughout its length within the imperforate tube to provide uniform heating of said heat exchanger even when said steam is throttled, said bends in said perforate-wall tubes accommodating expansion and contraction of said perforate-wall tubes and of said imperforate-wall tubes, said frame extending laterally outwardly beyond the sides and ends of said headers.

4. A steam-heated, air-heating, heat exchanger that comprises a plurality of heat-exchanging fins, each of said heat-exchanging fins having a plurality of openings therein, a plurality of imperforate tubes mounted in said openings in said heat-exchanging fins, said imperforate tubes being inclined to the horizontal to drain to the same end of the heat exchanger, said imperforate tubes projecting outwardly beyond both ends of said plurality of heat exchanger fins, a condensate header that is connected to the lower ends of said imperforate tubes, a steam header, a second steam header, a steam pipe communicating with and extending between said steam headers, a plurality of perforate tubes that communicate with and extend from said second steam header and that telescope into and through the lower ends of some of said imperforate tubes, the upper ends of said some imperforate tubes being closed, said perforate tubes being connected in parallel with each other, a second plurality of perforate tubes that communicate with and extend from said second steam header and that telescope into and through the upper ends of the rest of said imperforate tubes, the ends of said imperforate tubes through which said second plurality of perforate tubes telescope being sealed to said perforate tubes, said perforate tubes of said second plurality of perforate tubes being connected in parallel with each other, some of said perforate tubes extending through said condensate header, each of said perforate tubes having a bend therein intermediate its steam header and its said imperforate tube, said steam headers and said perforate tubes directing steam into the opposite ends of said heat exchanger, the perforations in each said perforate tube being spaced throughout its length within the imperforate tubes to provide uniform heating of said heat exchanger even when said steam is throttled, said bends in said perforate tubes accommodating expansion and contraction of said tubes and of said imperforate tubes.

5. A steam-heated, air-heating, heat exchanger that comprises a plurality of heat-exchanging fins, each of said heat-exchanging fins having a plurality of openings therein, a plurality of imperforate tubes mounted in said openings in said heat-exchanging fins, said imperforate tubes being inclined to the horizontal to drain to the same end of the heat exchanger, said imperforate tubes projecting outwardly beyond both ends of said plurality of heat-exchanging fins, a condensate header that is connected to the lower ends of said imperforate tubes, a steam header, a second steam header, a steam pipe communicating with and extending between said steam headers, a plurality of perforate tubes that communicate with and extend from the first said steam header and that telescope into and through the lower ends of some of said imperforate tubes, the upper ends of said some imperforate tubes being closed, a second plurality of perforate tubes that communicate with and extend from said second steam header and that telescope into and through the upper ends of the rest of said imperforate tubes, the upper ends of said imperforate tubes through which said second plurality of perforate tubes telescope being sealed to said perforate tubes, some of said perforate tubes extending through said condensate header, each of said perforate tubes having a bend therein intermediate its steam header and its said imperforate tube, said steam headers and said perforate tubes directing steam into the opposite ends of said heat exchanger, the perforations in each said perforate tube being spaced throughout its length within the imperforate tube to provide uniform heating of said heat exchanger even when said steam is throttled, said bends in said perforate tubes accommodating expansion and contraction of said tubes and of said imperforate tubes, the first said and said second steam headers being displaced laterally from said imperforate tubes and being disposed outwardly beyond said ends of said plurality of heat-exchanging fins.

6. A steam-heated, air-heating, heat exchanger that

comprises a plurality of imperforate tubes, said imperforate tubes being inclined to the horizontal to drain to the same end of the heat exchanger, a condensate header that is connected to the lower ends of said imperforate tubes, a steam header, a second steam header, a plurality of perforate tubes that communicate with and extend from the first said steam header and that telescope into and through the lower ends of some of said imperforate tubes, the upper ends of said some imperforate tubes being closed, a second plurality of perforate tubes that communicate with and extend from said second steam header and that telescope into and through the upper ends of the rest of said imperforate tubes, the upper ends of said imperforate tubes through which said second plurality of perforate tubes telescope being sealed to the perforate tubes, some of said perforate tubes extending through said condensate header, each of said perforate tubes having a bend therein intermediate its steam header and its said imperforate tube, said steam headers and said perforate tubes directing steam into the opposite ends of said heat exchanger, the perforations in each said perforate tube being spaced throughout its length within the imperforate tube to provide uniform heating of said heat exchanger even when said steam is throttled, said bends in said perforate tubes accommodating expansion and contraction of said tubes and of said imperforate tubes.

7. A steam-heated, air-heating, heat exchanger that comprises a plurality of imperforate tubes, said imperforate tubes being inclined to the horizontal to drain to the same end of the heat exchanger, each of said imperforate tubes being elongated and extending substantially the full length of the air heating portion of said heat exchanger, a plurality of perforate tubes that telescope into and through the lower ends of some of said imperforate tubes, the other ends of said some imperforate tubes being closed, a second plurality of perforate tubes that telescope into and through the ends of the rest of said imperforate tubes, the ends of said imperforate tubes through which said second plurality of perforate tubes telescope, being sealed to the perforate tubes, the first said plurality of perforate tubes starting adjacent one end of said heat exchanger and being directed toward the opposite end of said heat exchanger, said second plurality of perforate tubes starting adjacent the said opposite end of said heat exchanger and being directed toward the first said end of said heat exchanger, and a source of steam for said perforate tubes, each of said perforate tubes having a bend therein intermediate its imperforate tube and said source of steam, said perforate tubes directing steam into the opposite ends of said heat exchanger, the perforations in each said perforate tube being spaced throughout its length within the imperforate tube to provide uniform heating of said heat exchanger even when said steam is throttled, said bends in said perforate tubes accommodating expansion and contraction of said tubes and of said imperforate tubes.

8. A steam-heated, air-heating, heat exchanger that comprises a plurality of heat-exchanging fins, each of said heat exchanger fins having a plurality of openings therein, a plurality of imperforate tubes, said imperforate tubes being inclined to the horizontal to drain to the same end of the heat exchanger, each of said imperforate tubes being elongated and extending through the openings in said heat exchanger fins from one end of said heat exchanger to the other, each of said imperforate tubes being open at its lower end and closed at its upper end, a plurality of perforate tubes that telescope into and through the lower ends of some of said imperforate tubes, a second plurality of perforate tubes that telescope into and through the closed ends of the rest of said imperforate tubes, the first said plurality of perforate tubes starting

adjacent one end of said heat exchanger and being directed toward and terminating adjacent the first said end of said heat exchanger, said second plurality of perforate tubes starting adjacent the said opposite end of said heat exchanger and being directed toward and terminating adjacent the first end of said heat exchanger, and a source of steam for said perforate tubes, said perforate tubes directing steam into the opposite ends of said heat exchanger, the perforations in each said perforate tube being spaced throughout its length within the imperforate tube to provide uniform heating of said heat exchanger even when said steam is throttled.

9. A steam-heated, air-heating, heat exchanger that comprises a plurality of imperforate tubes, each of said imperforate tubes being elongated and extending substantially the full length of the air heating portion of said heat exchanger, said tubes each having an open end to the same end of the heater and a closed end at the other, each of said imperforate tubes being inclined downwardly to the open ends to facilitate drainage, a steam header at one end of said heat exchanger, a second steam header at the opposite end of said heat exchanger, a first plurality of perforate tubes approximately equal in number to one half the imperforate tubes extending from said one steam header through the open ends of said imperforate tubes toward the said opposite end of said heat exchanger, and a second plurality of perforate tubes equal in number to the balance of the imperforate tubes extending from said second steam header through the closed ends of said imperforate tubes toward the said one end of said heat exchanger, whereby steam is introduced into said heat exchanger at the opposite ends thereof, the perforations in each of said perforate tubes being spaced throughout its length within the imperforate tube to assure even steam distribution.

10. A steam-heated, air-heating, heat exchanger that comprises a steam header at one end of said heat exchanger, a second steam header at the opposite end of said heat exchanger, a plurality of perforate tubes extending from said one steam header toward and terminating adjacent the said opposite end of said heat exchanger, and a second plurality of perforate tubes extending from said second steam header toward and terminating adjacent the said one end of said heat exchanger, whereby steam is introduced into said heat exchanger at the opposite ends thereof, a plurality of imperforate tubes equal in number to the perforate tubes, all said imperforate tubes being open at one end and closed at the other, said imperforate tubes having their open ends to the same end of said heat exchanger and inclined to the horizontal to drain to the open ends, each of said perforate tubes being disposed within and encased by an imperforate tube, said first plurality of perforate tubes extending through the open ends of the encasing imperforate tube and said second plurality extending through the closed end of the encasing imperforate tube, said imperforate tubes being aligned to form a row of tubes, the said first and said second plurality of perforate tubes being interleaved whereby alternating imperforate tubes are fired from opposite ends of said heat exchanger, the perforations in said perforate tubes being spaced throughout their encased length to assure even steam distribution.
